Patented July 23, 1912.

UNITED STATES PATENT OFFICE.

WILLIAM HOCHFELDT, OF CHICAGO, ILLINOIS, ASSIGNOR TO SAFETY EQUIPMENT MANUFACTURING COMPANY, OF CHICAGO, ILLINOIS, A CORPORATION OF ILLINOIS.

PRESSURE REDUCING AND REGULATING VALVE.

1,033,174.

Specification of Letters Patent. Patented July 23, 1912.

Application filed February 27, 1911. Serial No. 611,923.

To all whom it may concern:

Be it known that I, WILLIAM HOCHFELDT, citizen of the United States, residing at Chicago, in the county of Cook and State of Illinois, have invented certain new and useful Improvements in Pressure Reducing and Regulating Valves, of which the following is a specification.

My invention relates to structural improvements in valves of the class described, adapted to facilitate frequent inspection, cleaning and reassembling without disturbing the adjustment.

The drawing shows a central longitudinal section of the valve along a plane extending both through the main fluid passage and also through the transversely positioned valve spindle and adjusting mechanism.

The valve casing consists of a main body part 1 containing the valve mechanism proper, and detachable cup elements 2 and 3 containing valve controlling and adjusting mechanism. The main casing body 1 has a hollow cavity divided by a partition into two compartments 4 and 5, into the former of which there opens a high pressure induction passage or port 6 and out from the latter of which there opens the low pressure eduction passage or port 6'. These ports are preferably threaded to engage suitable connecting pipes. In the embodiment which I have chosen to illustrate herewith, the said partition consists of a wall having two opposite portions 7 and 8 in which throttling valve ports 9 and 10 are located, said opposite portions of the partition being connected by a curved end portion 11. On one side of the main casing is integrally mounted a radially positioned cylinder 12 open at both ends. This cylinder is closed by a cup-shaped element 13 slidably embracing it on the outside, the bottom 14 of said cup serving to close the outer end of said cylinder 12. The said bottom 14 has a small perforation 15 to permit the escape of any fluid that may collect in said cup. The inner end of this cup is provided with an outwardly turned flange 16 against which pressure is received from a heavy spiral spring 17 engaging therewith which surrounds and extends outwardly beyond said cup 13. The large outer cup element 2, aforesaid, is threaded to the main casing body 1 at 18. The closed outer

end 19 of this outer cup 2 has a perforated central boss 20 in which is mounted an adjusting screw 21 pointing inwardly. The outer end of this screw has a slot 22 adapted to be turned by a screwdriver or the like. This outer end is protected from injury or accidental turning by means of an internally threaded cap 23 adapted to engage the threaded outer ends of said screw and fit tightly against the said boss 20 when in place. This cap has a cavity 24 in its upper portion to give clearance to the head of said screw. The lower end of this screw engages a disk 25 at its central point 26 where there is a conical depression adapted to receive the conical point 21' of the screw. An annular flange or radial shoulder is provided on disk 25 to engage the outer end of said spring 17. On the opposite side of the main casing body 1 from the said adjusting screw is an inwardly turned cup-shaped cylinder 3 threaded at 27 to the interior of a suitable opening provided therefor in the wall of the main casing 1. The inside of this cup is cylindrically shaped corresponding to the first said cylinder 12 on the opposite side. The said valve ports 9 and 10 have valves 28 and 29 co-acting therewith, said valves being mounted on a stem or spindle 30 on the opposite ends of which are attached pistons 31 and 32 coacting with the cylinders 12 and 3 respectively. The piston 32 is hollow and provided with a relatively weak spiral spring 33 on the inside, one end of which rests against the closed end 3' of the cup cylinder 3 and the other presses inward against the piston 32. This spring 33 serves only to keep the stem and valves pushed forward into co-active relation with the opposing spring 17 and prevents any possible looseness or uncertainty of action under different conditions of adjustment.

The stem 30 is provided with a transverse perforation 34 which, by means of a longitudinal perforation 35, connects from the eduction chamber to the interior of the cup-shaped piston 3.

The operation of my valve is as follows: When high pressure fluid, as steam, passes through the valve in the direction indicated by the arrows, it first enters the high pressure chamber 4 from whence it passes through the open valve ports 9 and 10 into

the low pressure chamber 5, and thence out through the passage 6'. As the valves are normally held open by means of the heavy spring 17 they will so remain until the pressure in the chamber 5 reaches the predetermined value. Then the pressure exerted on the piston 29 by the fluid which passes from the low pressure chamber 5 through the passages 34-35 and the pressure exerted 10 on the piston 31, will cause the valves 28 and 29 to close sufficiently to maintain the proper pressure.

It will be noted that the pistons 31 and 32 are provided with annular packing 15 grooves 36 and 37 respectively. These are preferably left open when steam is used, as in operation water of condensation tends to seep outward and fill the rings and serves as a packing sufficient for the purpose.

20 Whatever steam or other fluid escapes through the cylinder 12 past piston 31 finds its way out of the casing through the hole 15 in cup 13 and hole 38 in the side of cup 2.

When it is desired to clean the valve it is 25 only necessary to unscrew the cups 2 and 3, whereupon the various parts contained therein may be readily removed. Removal of cap 3 alone enables withdrawal of the stem 30 and valves 28 and 29 thereon. It 30 will be seen that in these operations the adjusting screw 21 is not affected. After the valve is reassembled, in case it is desired to change the adjustment, it is only necessary to remove the cap 23 and then turn the 35 screw 21 to whatever extent is necessary to maintain the desired pressure. This may be done best when the pressure is on.

The passages 34-35 may be omitted, in 40 which case the parts 3 29 32 serve as a dash- pot to retard the opening and closing move- ments of the valve. In use, water of con- 45 densation collects in the cap 3, and is forced in and out of the cap 3 through the space between the piston 32 and the cap 3, as the valve opens and closes.

While I have herein described more or less precisely the details of construction, I do not wish to be understood as limiting myself thereto, as I contemplate changes in 50 form, and the proportion of parts, and such other modifications as would occur to one skilled in the art, as circumstances may suggest or render expedient, without departing from the scope of my invention.

55 I claim as my invention:

1. In a fluid pressure reducing and regulating valve, in combination, a main casing body having fluid-inlet and outlet ports, inlet and outlet chambers into which said 60 ports lead respectively, a partition separating said chambers, said partition having a valve port therein, a valve co-acting with said valve port, a stem on which said valve is attached, pistons on opposite ends of said 65 stem, cylinders with which said pistons co-

act attached to opposite sides of said main casing and opening into said outlet chamber, a heavy spring pressing inward against one of said pistons tending to open said valve, protected and concealed means to adjust the pressure of said spring, a relatively weak spring pressing inward against the other of said pistons tending to close said valve, the cylinder with which the second 70 said piston co-acts being integrally closed at its outer end, and a fluid passage leading from the said outlet chamber to the interior of the said cylinder back of the second said piston.

2. In a fluid-pressure reducing and regulating valve, in combination, a main casing-body, having an induction port on one side and an eduction port on the other, corresponding chambers into which said ports lead respectively the one being contained 80 within the other, a curved partition separating said chambers and having opposite walls in which are valve ports respectively in co-axial alinement, valves co-acting with said valve ports respectively, a spindle on which 85 said valves are attached, pistons on opposite ends of said spindle, cylinders with which said pistons co-act attached to opposite sides of said main casing, and opening into the eduction chamber, a heavy spring pressing 90 inward against one of said pistons tending to open said valve, concealed and protected means to adjust the pressure of said spring, a relatively weak spring pressing inward 95 against the other of said pistons tending to close said valve, the cylinder with which the second said piston co-acts being integrally closed at its outer end, and a fluid passage leading from said eduction chamber to the interior of the said cylinder back of the sec- 100 on said piston.

3. In a device of the class described, in combination, a main casing-body, induction and eduction chambers respectively, a partition separating said chambers, a valve port 110 in said partition, main ports opening into said chambers respectively, a cylinder integral with said casing and opening into said eduction chamber at its inner end, a reciprocatory cup slidably embracing said cylinder and closing its outer end, a powerful spring pressing inward against said cup, a bearing plate engaging the outer end of said spring, an inwardly turned cup-shaped element inclosing said spring and detachably 115 engaging said body-casing, an adjusting screw radially positioned in the closed end of said spring inclosing cup-shaped element adjacent said bearing plate and co-acting with the latter to regulate the pressure of 120 said spring, a removable cap inclosing the outer end of said screw, an opening in said body-casing opposite said cylinder, an inwardly turned cup-shaped cylinder threaded within said opening, a valve co-acting 125 130

- with said valve port, a spindle on which said valve is mounted, a piston on each end of said spindle, one co-acting with the first said cylinder and engaging the closed end of the 5 said reciprocatory cup and the other co-acting with the cylindrical interior of the opposite cup-shaped cylinder, the latter piston being cup-shaped with its open end turned outward, a relatively weak spring co-acting 10 between the last said cup-shaped cylinder and co-acting piston, and a passage leading from said eduction chamber to the space back of the last said piston.
4. In a device of the class described, a 15 main casing, a partition separating same into two compartments, a high pressure port leading to one and a low pressure port to the other, a valve port in said partition, a valve co-acting with said port, a spindle on 20 which said valve is mounted, constant means acting on one end of said spindle tending to push said valve open, an outwardly turned cup-shaped piston attached to the other end of said spindle tending to push 25 said valve closed, a cylinder in which said piston co-acts, closed at its outer end, a compressed spring coacting between said cylinder and piston, and a passage in said
- spindle and piston leading from the low pressure chamber to the space in said cylinder back of said piston. 30
5. In a reducing valve, in combination, a body casing, an induction chamber and port therefor, an eduction chamber and port therefor, a partition between said chambers, 35 a plurality of ports in said partition, valves co-acting with the ports in said partition, one valve being on the induction side and another on the eduction side of said partition, rigid reciprocatory means to support 40 said valves, cylinders on opposite sides of said casing, pistons therefor, said pistons carrying said reciprocatory means for supporting the valves, said pistons having annular grooves adapted to collect water of 45 condensation to serve as packing, one of said cylinders being detachable, the said pistons and supporting means being removable as a whole when the said cylinder is detached. 50

In testimony whereof I affix my signature 50
in presence of two witnesses.
